BLANK-FEEDING DEVICE

Andrew Smith, Milwaukee, Wis., assignor to Van
Dyke Knitting Co., Milwaukee, Wis.

Application June 7, 1934, Serial No. 729,541

2 Claims. (Cl. 214—8.5)

This invention appertains to a novel machine for finishing discs, or chips, after the same have been cut or stamped out of strips of sheet material, and can be used in conjunction with the device shown in my Patent No. 2,073,320, entitled Feeding and blanking machine.

After the discs, or chips, have been stamped, or cut, out of the strips of cardboard or similar material, the same have more or less a rough appearance at their peripheries, and it is desirable to give the edges of the chips a finished smooth appearance, and to color this edge to agree with the body of the chips, in order that chips of a high grade, or quality, can be had.

It is, therefore, one of the salient objects of my invention to provide a machine embodying means for receiving a quantity of cut chips, or discs, and to deliver these chips to a novel feed mechanism utilized for carrying the chips on edge past a series of operating devices, such as a buffer, inker, polisher, etc., whereby to bring about the effective finishing of the chip edges.

Another important object of my invention is to provide novel means for conveying the chips on edge past the operating devices, including a plurality of parallel supporting feed screws, or worms, the threads of the screws acting to simultaneously feed a number of chips along the lengths thereof and to rotate the chips, whereby the edges of the chips around their entire peripheries will be acted on and effectively treated.

A further object of my invention is the provision of a magazine located at one end of the feed screws for receiving a stack of chips to be treated, with novel means for delivering the chips one at a time from the magazine to the feed screws, means being provided, operating in conjunction with the delivery means, to cant the chips and deliver the same on edge to the feed screws.

A further object of my invention is the provision of means for arranging a plurality of operating devices along the lengths of the feed screws to act on the edges of the chips as the same ride past the operating devices, novel means being provided for actuating said operating devices and to supply ink to the chip edges.

A still further object of my invention is to provide novel means for receiving the chips from the feed screws as the chips are fed off the screws, whereby the chips can be conveniently and expeditiously fed to a supplemental inking machine for coloring the opposite faces of the chips, where such is necessary.

With these and other objects in view, the in-

vention consists in the novel construction, arrangement, and formation of parts, as will be hereinafter more specifically described, claimed, and illustrated in the accompanying drawings, in which drawings:—

Figure 1 is a front elevation of my complete machine. 5

Figure 2 is a top plan view of the same, with the means for coloring the opposite faces of the chips removed. 10

Figure 3 is a longitudinal section through the device for inking the opposite faces of the chips, the view being taken substantially on the line 3—3 of Figure 4, looking in the direction of the arrows. 15

Figure 4 is a horizontal section, taken substantially on the line 4—4 of Figure 3. 15

Figure 5 is a detail vertical section, taken on the line 5—5 of Figure 1, looking in the direction of the arrows, illustrating the means for delivering the chips one at a time from the magazine 20 to the feed screws. 20

Figure 6 is a fragmentary, detail horizontal section, taken substantially on the line 6—6 of Figure 5, looking in the direction of the arrows. 25

Figure 7 is an enlarged, fragmentary detail view, illustrating the means for canting the chips to deliver the same on edge to the feed screws. 25

Figure 8 is a similar view, showing the chip in another position. 30

Figure 9 is a detail section through the feed screws, taken at right angles to Figures 7 and 8. 30

Referring to the drawings in detail, wherein similar reference characters designate corresponding parts throughout the several views, the letter A generally indicates my improved chip-finishing machine, and the same includes a suitable supporting base frame 15, having a supporting platform 16 arranged in a horizontal plane at its upper end. One end of the supporting platform 16 extends materially beyond the supporting base frame 15, for a purpose which will be later set forth. 35

The platform 16, at its opposite ends, supports bearing brackets 17 for a plurality of longitudinally extending, spaced, parallel feed screws, or worms, 18, 19, and 20. The feed screws 18 and 19 are arranged in the same horizontal plane, and the shaft parts thereof are spaced a sufficient distance apart to receive a chip therebetween, so that the chip will be engaged by the threads. The feed screw 20 is arranged below and directly between the feed screws 18 and 19, and the chips rest on this bottom screw. The terminals of the feed screws, at one end of the machine, extend 45

into a gear box 21 for housing the gears 22 utilized for connecting all of the feed screws together, whereby the feed screws will rotate in unison and in the proper direction for feeding chips from one end of the feed screws to the other.

Disposed in rear of the feed screws is a main drive shaft 23, and this shaft extends longitudinally of the platform. A counter-shaft 24 also extends longitudinally of the platform between the main drive shaft 23 and the feed screws 18, 19, and 20, and is operatively connected to the drive shaft 23 by any preferred mechanism, such as a sprocket chain 25 and sprocket wheels 26.

The shaft 24 is in turn provided with a drive gear 27, located in the gear box, for meshing engagement with one of the gears 22. The drive shaft 23 can be operated from any desired source of power, and one end of the same can be provided with a pulley 28 for a power belt.

Arranged transversely of the platform 16, in proper spaced relation, is a series of devices for operating on the chips as the same are fed longitudinally of the platform by the feed screws. These devices include a buffering mechanism 29, an inking mechanism 30, a polishing device 31, and a second inking mechanism 32. These devices will be described in detail at a later point.

It is essential to provide means for quickly and accurately delivering chips one at a time on edge to the feed screws, and such a mechanism is shown in the drawings at the lefthand side of the machine (Figures 1 and 2).

The feed mechanism includes a vertically extending hopper 33 for receiving a stack of chips, and the upper end of the magazine is open to facilitate the placing of the chips in the magazine by an operator. This magazine can be supported by a bracket 34, connected with the platform 16, and the lower end of the magazine is spaced the thickness of a chip from a feed plate 35.

Operating between the lower end of the magazine and the feed plate is a pusher head 36 formed on the forward end of a rock arm, or lever, 37. This rock arm, or lever, 37 is mounted intermediate its ends on a vertically extending pivot 38 carried by the platform, and the rear end of said lever, or arm, carries a pin, or roller, 39 for movement in a cam slot 40 formed in the periphery of the cam wheel 41.

This cam wheel is keyed, or otherwise secured, to the main drive shaft 23, and consequently during the rotation of the shaft, the arm will be rocked for alternately moving the pusher head 36 across the face of the feed plate 35 and below the magazine 33 for carrying the lowermost chip from the magazine to the feed screws. Thus, the chips can be delivered one at a time from the magazine. In Figure 8 of the drawings, the pusher head is shown in its extreme position and under the magazine.

As the chips are disposed in a horizontal plane, it is necessary to cant the chips as the same are pushed from the magazine, so that the chips will be delivered in a vertical plane and on edge between the feed screws 18 and 19.

I have provided means for tapping the projecting edge of a chip as the same protrudes beyond the feedplate. This means includes a tap arm 42 rockable intermediate its ends on a pivot pin carried by the gear box. The rear end of the tap arm carries a pin, or roller, 43, which travels in a cam slot 44, formed in the outer face of a cam wheel 45 keyed to the main drive shaft 23. The forward end of the tap arm is provided with

a tap pin 46 located at one side of the magazine.

Hence, during rotation of the shaft 23, the tap arm will be alternately raised and lowered at its front end to bring the tap pin down into engagement with the projecting edge of a chip. This serves as means for tapping the chip, so as to insure the delivery thereof in a vertical plane and on edge to the feed screws. Obviously, the tap arm 42 and the rock lever 37 operate in proper timed relation.

As stated, as the chips are fed along the platform by the feed screws, the same are acted on by the devices 29, 30, 31, and 32, and the feed screws serve the additional function of rotating the chips during their traveling movement.

The buffering device 29 includes a swinging yoke 50, having its rear end provided with spaced journals 51 rotatably mounted on the shaft 23. Rotatably supported by the yoke is a driven shaft 52, and keyed, or otherwise secured, to this shaft is a buffering wheel 53. This wheel is relatively wide so as to insure the effective operation thereof on the chips as the chips are moved past the same.

In order to rapidly rotate the shaft 52, the same can have secured thereto a pulley wheel 54, around which is trained a pulley belt 55. This belt 55 is in turn trained about a relatively large drive pulley wheel 56, keyed to the drive shaft 23.

By this arrangement, it can be seen that the yoke freely rocks on the shaft 23, and that the buffering wheel 53 is normally urged by gravity toward the feed screws and into engagement with the chips. The buffering wheel 53 effectively smooths the rough edges of the chips, and as the chips leave the buffering wheel, the same have their edges inked by the inking device 30.

The inking device 30 embodies a main inking roll 57, which can be keyed, or otherwise secured, to the driven counter-shaft 24. In rear of the main inking roll 57 is an ink fountain 58, having rotatably mounted therein an ink feed roll 59.

This ink feed roll 59 engages an intermediate inking roll 60, which in turn presses against the main ink roll 57, and the rolls 59 and 60 are actuated from the main roll 57. The roll 59 functions to carry the ink from the fountain to the roll 60, and this roll then supplies the ink to the main inking roll 57.

It is essential that the ink be uniformly supplied over the face of the main inking roll 57, and consequently a plurality of distributing rolls 61 are provided. These distributing rolls 61 are secured to rotatable and slidable shafts 62, and the shafts carry collars, or rollers, 63 for traveling movement in cam grooves 64 formed in the periphery of the main roll 57. Thus, during rotation of the roll 57, the distributing rolls will be rotated and slid longitudinally of the main roll for distributing the ink thereover.

The main roll 57 is utilized for uniformly supplying the ink to the chip inking roll 65, and the same is in contact therewith. The chip inking roll 65 is located directly above the feed screws, and is adapted to engage the edges of the chips as the same are moved past the device 30.

As the chips ride past the inking device 30, the same are acted upon by the polishing device 31, which serves as means for forcing the ink into the piper fibres of the chips, and to calender, or gloss, the chip edges.

The device 31 is constructed similar to the buffering device 29, and consequently includes a swinging yoke 66. The yoke 66, at its rear end, carries journals 67, which are rotatably mounted

- on the drive shaft 23. Rotatably mounted on the yoke, above the feed screws, is a driven shaft 67 to which is keyed the polishing wheel 68. Also keyed, or otherwise secured, to the shaft 67 is a relatively small pulley wheel 69, around which is trained the drive belt 70. The drive belt 70 is in turn trained over a relatively large drive pulley wheel 71, keyed, or otherwise secured, to the drive shaft 23.
- 10 The polishing wheel 68 is normally held by gravity into engagement with the periphery of the chips, and this wheel is also relatively wide so as to insure the proper action as the chips ride past the same.
- 15 Adjustable stops 72 are provided for the yokes 50 and 66 of the devices 29 and 31, and these stops can be carried by brackets 73, bolted, or otherwise secured, to the platform 16. The yokes extend above the stops and can rest in their extreme lowered position thereon.
- 20 Means is provided for raising the yokes on the stops, so that the wheels 53 and 68 can be held in a raised inoperative position above the chips. This means can simply embody cam levers 74, 25 rockably supported by the forward ends of the yokes, and the cam portions of the levers are adapted to be moved into and out of engagement with the stops.
- 25 The inking device 32 serves as means for giving the polished edges of the chips an additional coat of ink, and the same is constructed similar to the inking device 30, and hence will not be described in detail. It is to be noted, however, that the chip inking roll is relatively longer than 30 the chip inking roll 65 of the inking device 30, as it is desirable that sufficient ink be supplied to the edges of the chips around their entire peripheries.
- 35 The chips, as they leave the feed screws, may 40 be guided into a suitable container and then packed for shipment. However, in a better grade of chips, white stock is utilized, and the faces of the chips are acted upon by a supplemental inking machine 75 to give the same the desired color.
- 45 This machine 75 extends transversely of the machine A and is positioned under the extended portion of the platform 16. As shown, the machine 75 comprises a frame 76, including a plurality of supporting legs 77. The legs 77 support a pair of spaced parallel supporting side plates 78 and a bottom plate 79.
- 50 Between the opposite ends of the plate 78 are arranged fountains, or reservoirs, 80 for reception of the desired color of ink. Located directly 55 at the transverse center of the inking machine 75 is a pair of chip inking rolls 81 and 82, and the chips are adapted to be carried between these rolls which apply the ink to the opposite faces 60 thereof.
- 65 Means is provided for carrying and distributing the ink from the fountains, or reservoirs, 80 to the chip inking rollers 81 and 82. This means can include main ink distributing rollers 83 and 84, which are located between the chip inking rollers 81 and 82 and the fountains, or reservoirs, 80. It will be noted that the main ink distributing rollers 83 and 85 engage the inking rollers 81 and 82.
- 70 Disposed in each reservoir 80 for carrying ink therefrom is a rotatable roller 85, and the ink is carried from the rollers 85 to the distributing rollers 83 and 84 by means of swinging rollers 86, the shafts of which are carried by rock arms 87, 75 secured to rock shafts 88.

To facilitate the equal distribution of the ink over the distributing rollers 83 and 84, a plurality of small rollers 89 are provided for each of the main distributing rollers 83 and 84. The small rollers 89 are in frictional contact with the periphery of the rollers 83 and 84, and are slid transversely of the rollers 83 and 84 during the rotation thereof. This is brought about by the use of collars, or rollers, on the shafts of the small rollers 89, which travel in cam grooves 90, 10 formed in the periphery of the main distributing rollers 83 and 84.

The side plates 78 of the frame form the journals for the various shafts, and it will be noted that the shafts for the main distributing 15 rolls 83 and 84 have keyed thereto relatively large intermeshing gears 91. One of these gears has meshing therewith a drive pinion 92, keyed, or otherwise secured, to a transversely extending main drive shaft 93. This main drive shaft 20 93 can be driven from any suitable source of power, and the same can be provided with a pulley wheel 94 for the reception of a drive belt.

If desired, the ink carrying rollers 85 of the fountains 86 can be intermittently operated from 25 the shafts for the main distributing rollers 83 and 84, and thus these shafts can have keyed, or otherwise secured, thereto crank wheels 95, which actuate pitmans 96.

These pitmans in turn can actuate swinging 30 levers 97, having dogs 98 for operative engagement with ratchet wheels 99 on the shafts of the rollers 85. Likewise, the rock arms 87 for the ink carrying rolls 86 can be actuated from the pitmans 96.

35 By referring to Figure 1 of the drawings, it can be seen that a hopper 100 receives the chips from the feed screws 18, 19, and 20. Depending from the hopper 100 is a guide chute 101, and this chute leads to the inking machine 75, and terminates 40 directly above and between the chip inking rollers 81 and 82. Thus, as the chips fall from the chute, they are grasped between the chip inking rollers 81 and 82.

To facilitate the movement of the chips through 45 the outlet opening 102, oppositely rotating feed shafts, or rollers, 103 are provided. The direction of rotation of the chip feeding rollers 103 is toward one another, and thus as the chips fall, the same will strike the rotating shafts, which will 50 throw the same toward the opening. If desired, guide plates 104 can extend from the feed shafts 103 to the sides of the opening 102. Directly below the opening 102 is a removable container 105 for receiving the chips.

55 To bring about the proper rotation of the shafts 103, the same are geared together by means of pinions 106 keyed to the respective shafts. One of the shafts 103 can be extended beyond the frame, and this extended portion of the shaft 60 has keyed thereto a pinion 107, which meshes with one of the gears 91.

From the foregoing description, it can be seen that I have provided means for quickly and efficiently handling chips in quantities to give the 65 same a finish and a quality appearance.

Changes in details may be made without departing from the spirit or the scope of my invention, but what I claim as new is:—

1. In a machine for finishing poker chips of 70 the type having a plurality of longitudinally extending feed screws for conveying chips on edge; a device for feeding the chips on edge one at a time to the feed screws including a vertically disposed magazine for receiving a stack of the chips 75

arranged above the feed screws at one end thereof, a stationary feed plate disposed below the magazine, a swinging push lever movable over the feed plate to carry the lowermost chip from the magazine, and a rocking tap rod for striking the chips as the same leave the feed plate for causing the canting thereof and the dropping of the same vertically between the feed screws.

2. In a machine for finishing poker chips of the type having a plurality of longitudinally extending feed screws for conveying chips on edge; a device for feeding the chips on edge one at a time to the feed screws including a magazine disposed in a vertical plane above the feed screws at one end thereof for receiving a stack of chips, a stationary feed plate disposed below the magazine and slightly spaced therefrom, an operating

shaft, a cam wheel on said shaft having a cam track on its outer face and a cam track on one side face, a rocking lever pivotally mounted on a vertical pivot intermediate its ends having a follower pin disposed in the cam track on the outer face of the cam wheel, and a push plate on its forward end movable over the feed plate for carrying a chip from the feed plate below the magazine, and a tap rod rockably mounted intermediate its ends on a horizontal pivot having a follower pin engaging in the cam track on the side face of the cam wheel, and a tap pin on its forward end for striking the chips as the same leave the feed plate for causing the canting of the chips and the dropping of the same vertically between the feed screws.

ANDREW SMITH.
